UNITED STATES PATENT OFFICE.

AUGUST KEHM, OF CHICAGO, ILLINOIS.

RADIATOR-SUPPORT.

1,244,613.

Specification of Letters Patent. Patented Oct. 30, 1917.

Application filed March 29, 1916. Serial No. 87,520.

To all whom it may concern:

Be it known that I, AUGUST KEHM, a citizen of the United States, and resident of Chicago, county of Cook, and State of Illinois,

5 have invented certain new and useful Improvements in Radiator-Supports, of which the following is a specification, and which are illustrated in the accompanying drawings, forming a part thereof.

10 The invention relates to a wall bracket for supporting radiators of that type which have hitherto been usually supported by being provided with a base or legs which stand upon the floor. The great importance 15 now attached to the practice of avoiding the use of permanent obstructions of any kind upon the floors of rooms, particularly in hospitals, schools and the like, where cleanliness is essential, and the improved appearance 20 obtained by constructing radiators without a base, render it desirable to provide a simple and effective means for supporting the radiators from the wall. The object of the invention is accordingly to provide 25 a wall support for radiators of the type described which shall be of simple construction but effective in service and arranged to permit a convenient installation of the radiator in the required position.

30 In the accompanying drawings,

Figure 1 is a side elevation of the improved radiator support with the radiator and details of the wall and floor of the room shown in section,

35 Fig. 2 is a front elevation of the parts shown in Fig. 1, a detail of the floor being shown in section,

40 Fig. 3 is a detail central, vertical, sectional view of the improved radiator support, the bracket being partly shown in elevation,

Fig. 4 is similar to Fig. 1, but shows a modified form of construction, and

45 Fig. 5 is a detail perspective view showing the construction of some of the parts.

The invention is more particularly concerned with providing a support for radiators which comprise a plurality of upright loops, as 10 (Figs. 1 and 2), or 11 (Fig. 4).

50 These loops are arranged side by side with a sufficient intervening space 12 (Fig. 2) to permit of a free circulation of air about the loops and adjacent loops are connected at their lower ends by horizontal nipples, as 13 or 14. Furthermore, each loop comprises a

plurality of upright columns with openings, as 15 or 16, between adjacent columns throughout the greater portion of their length.

In carrying out the invention upright 60 wall plates, as 17 or 18 are secured against the wall immediately in rear of the place where the radiator is to be supported. These wall plates will vary in length in accordance with the height of the loops, as 10 or 11, of the radiator, and the number of wall plates employed may vary with the length of the radiator, though two such plates will usually be employed with radiators of ordinary length. In most instances, lag screws, 65 as 19, 20 or 21, 22, will serve for securing the wall plates 17 or 18 against the wall. The radiators are primarily supported by bracket arms 23 or 24, one of which projects outwardly from each of the wall plates 17 or 18. These bracket arms are preferably of reduced width to permit of their entering the space, as 12, between adjacent loops 10 or 11 of the radiator.

70 A stirrup 25 hangs from the outer end of the bracket arm 23 or 24 for receiving the corresponding nipple 13 or 14 of the radiator. In order that this stirrup may be fitted about the radiator nipple it is preferably made openable and is detachably connected with the corresponding bracket arm 23 or 24. As shown, the stirrup 25 is formed in two parts or halves 26, 27, and these parts are hingedly connected at their lower ends with a hinge pin or pivot 28. 75 To facilitate the detachable connection of the stirrup 25 with the bracket arm 23 or 24, the bracket arm is provided with a depending head 29 at its outer end. This head is of flaring shape to be received between the two parts 26, 27, of the stirrup 25, when in closed position, and each of the front and rear faces of the head 29 is formed with a socket 30 for receiving an instanding lug 32 which is provided at the upper end of the 80 corresponding part 26, 27 of the stirrup. Preferably the axes of the sockets 30 are normal to the corresponding faces of the head 29. The two sockets 30 are therefore somewhat downwardly inclined and provide a firm support for the stirrup upon the bracket arm 23 or 24. If desired, the front and rear faces of the head 29 may also be grooved below the corresponding socket 30, as at 31, (Fig. 5) to prevent lateral dis- 85

90 95 100 105 110

placement of the stirrup. When the parts of the stirrup are closed about one of the nipples 13 or 14 of the radiator and engaged with the head 29 of the corresponding bracket arm 23 or 24, the entire weight of the radiator may be received by the stirrup.

As it may be inconvenient to accurately locate the wall plates, as 17 and 18, upon the wall for supporting the radiator in the required position, each bracket arm 23 or 24 is preferably so connected with the corresponding wall plate 17 or 18 that it may be vertically adjusted. As shown, a connecting plate 33 is provided upon each wall plate 17 and 18 for engagement with the corresponding bracket arm. This connecting plate may be secured in position upon the wall plate by one of the lag screws, as 19 or 22, employed for holding the wall plate against the wall. In that event the lag screw 19 or 22 passes through the upper end of the connecting plate 33 and lateral displacement of the connecting plate is prevented by the provision of a stud 34 at its lower end for entering a socket 35 in the wall plate.

The connecting plate 33 further has a chambered body 36 for receiving the head 37 of a clamping bolt 38. To permit the use of the clamping bolt for attaching the bracket 23 or 24 to the connecting plate 33 throughout quite a range of vertical adjustment, the bolt opening 39 in the chambered body 36 of the plate is vertically slotted. When so constructed, the face 40 of the plate 33, at each side of the opening 39, is serrated for the engagement therewith of the serrated inner end 41 of the bracket 23 or 24 in any adjusted position.

In practice the radiator is readily installed, if it is initially supported at the required elevation upon jack screws (not shown). One of the stirrups 25 is then fitted about the nipple 13 or 14 in front of each wall plate 17 or 18 and is engaged with the corresponding bracket arm 23 or 24 by closing the ends of the stirrup upon the head 29, of the bracket arm with the projecting lugs 32 entered in the sockets 30. The bracket arm 23 or 24 is then brought to a suitable elevation for the engagement of the bottom of the stirrup with the under side of the nipple 13 or 14, and firmly secured in adjusted position by tightening the corresponding clamping bolt 38. When this operation has been completed for each support with which the radiator is to be provided, the jack screws may be withdrawn from beneath the radiator.

Any convenient means may be employed for holding the radiators in upright position in the stirrups 25. If desired, a T-headed bolt 42 or 43 may be employed for this purpose, the bolt being entered in the

space between two adjacent loops 10 or 11 65 of the radiator when the T-head of the bolt is in upright position. The bolt is then rotated to bring the arms of this T-head to horizontal position in which case they serve to hold the radiator upright by entering the 70 openings, as 15 or 16 in the radiator-loops at opposite sides of the bolt.

When the radiator is composed of short loops, as 11, (Fig. 4) the T-headed bolt, as 43, may be supported by having threaded 75 engagement with the outer end of the bracket arm 24. When radiators with longer loops, as 11 (Figs. 1 and 2), are employed, the wall plate, as 17, preferably extends for a considerable distance above the 80 bracket arm 23 and the T-headed bolt, as 42, is located at the level of the higher end of the wall plate. In this instance, a screw threaded socket 44, is mounted upon the wall plate 17 for receiving the stem of the 85 bolt 42. As shown, the socket 44 is secured against the wall plate 17 by one of the lag screws, as 20, which also serves for holding the wall plate 17 against the wall. Under these circumstances rotation of the socket 90 44 about the lag screw 23 is prevented by providing the said socket with a stud 45 which enters an opening 46 in the wall plate 17 above the lag screw. It has been found convenient to extend the walls of the socket 95 44 forwardly for a considerable distance beyond the screw threaded portion, as 47, with which the threaded stem of the bolt 42 is to be engaged, as at 48 (Fig. 3). This forwardly extended portion of the socket has a 100 smooth interior surface and serves for initially receiving the stem of the bolt 42. It follows that if the bolt 42 is released, upon being entered in the socket, before being engaged with the threaded portion 47, the extended portion 48 of the socket will prevent the bolt from falling to the floor.

The invention provides a radiator support which is quickly applied and which is substantially concealed when in use. Furthermore, the construction of the support is such that the vibrations of the radiator are not communicated to the attaching bolts. Loosening of the support in use is thereby effectively avoided.

I claim as my invention,—

1. A concealed hanger for radiators having upright loops with inner and outer columns and horizontal nipples connecting the lower ends of the loops, comprising, in combination, an upright wall plate, a bracket arm projecting outwardly from the lower end of the wall plate for entering the space between adjacent loops of the radiator, an operable stirrup hanging from the outer 125 end of the bracket arm for receiving the nipple connecting the said radiator loops, and a rotatable T-head bolt projecting out-

wardly from the upper end of the wall plate to pass between the said adjacent loops of the radiator when the T-head of the bolt is upright and to enter the spaces between the 5 inner and outer columns of the said adjacent loops of the radiator when the T-head of the bolt is turned to a horizontal position.

2. In a device of the kind described, in 10 combination, a horizontal bracket having a depending head which flares in the plane of the bracket and is provided with a socket in each of its flaring sides, and an openable U-shaped stirrup having instanding lugs at 15 the upper ends of its two arms for removably entering the said sockets in the head of the bracket.

3. In a device of the kind described, in 20 combination, a horizontal bracket having a depending head with sockets in the front and rear faces of the head, and an openable U-shaped stirrup having instanding lugs at the upper ends of its two arms for removably entering the sockets in the head 25 of the bracket.

4. In a device of the kind described, in combination, an upright wall plate, an upwardly facing seat for the bottom of a radiator carried by the wall plate adjacent its 30 lower end but located at a distance outwardly from the wall plate, and a horizontal bolt having a head which is of different widths in relatively transverse directions to pass between the upright loops of a radiator in one position but to engage the columns of two adjacent loops 35 when turned to a different position, rotatably connected with the wall plate above the said seat.

a different position, rotatably connected with the wall plate above the said seat.

5. In a device of the kind described, in combination, an upright wall plate, an upwardly facing seat for the bottom of a radiator 40 adjustably connected with the wall plate adjacent its lower end to be supported thereby in vertically adjusted position at a distance outwardly from the wall plate, 45 and a horizontal bolt having a head which is of different widths in relatively transverse directions to pass between the upright loops of a radiator in one position but to engage the columns of two adjacent loops 50 when turned to a different position, rotatably connected with the wall plate above the said seat.

6. In a device of the kind described, in combination, an upright wall plate, a horizontal bracket arm having one end adjustably connected with the wall plate adjacent its lower end to be supported thereby in vertically adjusted position, an openable stirrup for receiving the connecting nipple 60 between two adjacent radiator loops hanging from the other end of the said bracket arm, and a horizontal bolt having a head which is of different widths in relatively transverse directions to pass between the 65 said radiator loops in one position but to engage the columns of the two loops when turned to a different position, rotatably connected with the wall plate above the said bracket arm.

AUGUST KEHM.
